UNITED STATES PATENT OFFICE.

LENA M. KIRCHNER, OF KANSAS CITY, MISSOURI.

DUSTER.

Specification of Letters Patent. Patented Aug. 27, 1918.

1,276,933.

Application filed July 17, 1916. Serial No. 109,719.

To all whom it may concern:

Be it known that I, LENA M. KIRCHNER, a citizen of the United States, residing at Kansas City, in the county of Jackson and 5 State of Missouri, have invented certain new and useful Improvements in Dusters; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 My invention relates to dusters, or mops and has for its principal object to provide a device of this character which is particularly adapted for dusting and cleaning polished floors and furniture, and to provide a 20 cleaning portion, which is easily removable from the frame portion to permit it to be washed or cleaned.

A further object of the invention is to connect the handle and frame portions in such a 25 manner as to facilitate the use of the duster in corners, or under furniture.

In accomplishing these objects I have provided improved details of structure, the preferred forms of which are illustrated in the 30 accompanying drawings, wherein:—

Figure I is a perspective view of a duster, or mop constructed according to my invention.

Fig. II is a perspective view showing the 35 mop or duster portion removed from the frame.

Fig. III is a sectional view through the duster head.

Fig. IV is a detail view of the circular 40 frame band, particularly illustrating the joining collar.

Referring more in detail to the drawings:—

1 designates a duster embodying my invention, comprising a duster head 2, which is pivotally mounted at the end of a handle 3.

The duster head is carried on a frame comprising a band, or ring 5, which is pivotally

carried within an aperture 6 at the end of 50 the handle 3; the ends of the band 5 being provided with right and left hand threads and joined by an internally threaded collar 7.

Inclosing the frame band 5 are padding 55 tubes 8, which are formed by folding fabric strips and sewing the same to provide tubes, which are slipped over the band ends to inclose the same therein.

Inclosing the padded ring frame is a fabric bag 11, which is provided at its opening edge with a hem 12 through which a draw string 13 is run, and by which the open end of the bag may be drawn together and closed about the frame, and sewed or otherwise 65 secured to the bag at the periphery of the frame is a fringe 14 of closely packed yarn strands which are adapted for gathering dust from the object on which the duster is 70 used.

Presuming the parts to be so constructed, in assembling the device, the frame ring is projected through the handle aperture and drawn therein until the handle is at a point diametrically opposite the ring ends, the 75 packing tubes are then projected over the ring and the ends of the ring joined by the collar 7.

The bag having the fringe yarn attached thereto is then drawn over the frame and the 80 bag opening closed thereover by tightening the draw string 13, and the duster is ready for use.

It is apparent that a duster of this character may be used for dusting polished floors 85 or furniture without any danger of scratching or otherwise marring the surfaces thereof.

It is also apparent that when it is desired or necessary the duster may easily be removed from the frame after loosening the draw string, so that the fringe and bag parts may be washed, and run through a wringer the same as other fabric.

I have described the device as a duster, 95 but it is apparent that it may be used equally as well as a mop and if it is desired, the fringe strands may be oiled.

Having thus described my invention, what I claim as new therein, and desire to secure by Letters-Patent, is:—

The combination with a handle having an 5 end aperture and a frame comprising a circular band extending pivotally through said aperture, of a mop comprising a bag adapted to receive said frame and having a slit down

the side thereof for receiving said handle, and having a hem about the open end thereof, a draw string extending within the hem whereby the bag may be closed about the frame and polishing material attached to the bag for the purpose set forth.

In testimony whereof I affix my signature. 15
LENA M. KIRCHNER.
